DESIGN FOR A TISSUE PACKAGE

William Medoff, Forest Hills, Long Island, N. Y.

Application June 13, 1942, Serial No. 107,185

Term of patent 14 years

To all whom it may concern:

Be it known that I, William Medoff, a citizen of the United States, residing at Forest Hills, Long Island, in the county of Queens and State of New York, have invented a new, original, ornamental Design for a Tissue Package, of which the following is a specification, reference being had to the accompanying drawing, forming part thereof.

In the drawing,

Fig. 1 is a perspective view of a tissue package showing my new design;

Fig. 2 is a bottom plan view thereof.

I claim:

The ornamental design for a tissue package, substantially as shown.

WM. MEDOFF.
